United States Patent Office

Des. 229,712

Patented Dec. 25, 1973

229,712

CIGARETTE LIGHTER

Jerome P. Vogel, Woodland Hills, Calif., assignor to Lindy Pen Company, Incorporated

Filed Sept. 5, 1972, Ser. No. 286,619

Term of patent 14 years

Int. Cl. D27—05

U.S. Cl. D48—27 R

FIG. 1 is a perspective view of a cigarette lighter showing my new design.

FIG. 2 is a side elevational view thereof on an enlarged scale.

FIG. 3 is an elevational view of the left side of FIG. 2.

FIG. 4 is an elevational view of the right side of FIG. 2.

FIGS. 5 and 6 are, respectively, top and bottom plan views thereof of an enlarged scale.

I claim:

The ornamental design for a cigarette lighter, as shown and described.
